BOTTLE CAP

William C. Sentman, Kellogg, Idaho, assignor of
one-half to Oscar G. Reiman, Kellogg, Idaho

Application November 11, 1935, Serial No. 49,313

3 Claims. (Cl. 215—9)

This invention relates to caps for bottles and more particularly to screw caps.

An object of the present invention is to provide a safety screw cap particularly designed for use on bottles containing a poison or the like and which is of such a construction, combination and arrangement of parts as only one thoroughly familiar with the structure of the cap can, other than by chance, properly remove the cap from the bottle.

The invention together with its objects and advantages will be best understood from a study of the following description taken in connection with the accompanying drawing wherein:

15 Figure 1 is a view showing in section the improved cap with the parts so arranged as to permit the relative movement thereof.

Figure 2 is a view similar to Figure 1 with the parts so relatively arranged and engaged as to transmit movement of one part of the cap to the other to effect a removal or replacement of the cap.

Figure 3 is a detail view taken substantially on the line 3—3 of Figure 1, and

25 Figure 4 is a sectional view through the outer or false cap member.

Referring to the drawing by reference numerals it will be seen that the cap, in the preferred embodiment thereof, comprises in accordance with the present invention a main cap 7 consisting of a suitably shaped body, preferably a cylindrical body having a threaded socket portion 8 for the threaded reception of the neck 9 of a conventional bottle 10. If desired there may be suitably arranged in the inner end of the socket of the cap 7 a cork or other sealing element 11.

The cap member 7 is housed within what may be termed a false cap member 12.

The cap member 12 which may be formed of metal or other suitable material is materially larger than the cap member 7 and is in the form of a closed casing except for an opening 13 in the bottom thereof registering with the socket 8 and accommodating the neck 9 of the bottle 10.

45 The cap member 12 is normally loosely mounted with respect to the cap member 7 so that the member 12 may be rotated or otherwise manipulated without normally affecting the cap member 7.

50 Further in accordance with the present invention the cap member 7 in the crown thereof is provided at any two desirable points thereon with sockets or recesses 14 while the cap member 12 on the under side of the crown part thereof is 55 provided with protuberances or pins 15 cooper-

able with the sockets 14 for placing the cap member 12 in such engagement with the cap member 7 that a rotative movement of the member 12 will be imparted to the cap member 7 either for screwing the cap onto the neck or for unscrewing 5 the cap from the neck of the bottle.

Interposed between the crowns of the cap members 7 and 12 is a spring device in the form of a disk 16 of spring metal or the like secured to the crown of the cap 7 at the center of said crown 10 and in any suitable manner. Radiating from the disk 16 are upwardly directed curved fingers 17 that normally engage the crown of cap 12 to yieldably hold the crown of the cap 12 raised with respect to the crown of the cap 7 and consequently the projection 15 out of engagement with the recesses 14.

From the above it will be apparent that normally the cap members are in the relative position shown in Figure 1.

When for example it is desired to remove the cap from the neck 9 a downward pressure is exerted on the cap member 12 against the opposition of spring fingers 17 and the member 12 is also properly rotated relative to the member 7 to position the protuberances or projections 15 into engagement with the recesses 14 for locking the cap members 12 and 7 together. When thus locked together rotative movement of the cap member 12 in the proper direction will be imparted 30 to the member 7 for unscrewing the member 7 to remove the cap from the bottle.

To replace the cap pressure is exerted on the cap member 12 to engage the projections 15 with the recesses 14 and while so engaged the rotation 35 of the member 12 in the proper direction will result in a transmission of movement to the member 7 for threading the same onto the bottle neck 9.

It will be seen that a cap of this character will 40 require certain knowledge on the part of the user as to the construction of the cap before a removal of the cap can be effected other than perhaps by chance. Thus a cap of this character will be especially useful for use by druggists and 45 the general public for containers containing poison or other kinds of medicine or the like that is not to be opened by children or persons under irrational impulses.

Having thus described the invention, what is 50 claimed as new is:

1. In a cap of the character described, inner and outer complemental cap members, said inner cap member fitting loosely within the outer cap member, a disk interposed between the crowns of 55

said cap members and secured to the crown of the inner cap member, and upwardly directed curved fingers integral with the edge of said disk and engaging the crown of the outer cap member for 5 yieldably retaining the crowns of said cap members in spaced relation, and inter-engaging means on the crowns of said cap members adapted to be engaged in opposition to said fingers for transmitting movement of the outer cap member 10 to the inner cap member.

2. A cap for bottles or the like comprising an inner cap adapted to be applied to a bottle or the like by turning it, an outer cap covering the inner cap, means retaining the caps assembled but 15 permitting relative rotary movement thereof, a spring device interposed between the crowns of said cap members yieldably spacing said crowns apart, said inner cap member having recesses in the crown thereof, and said outer cap member

having internal protuberances on the crown thereof and adapted to engage said recesses in opposition to the spring device for releasably securing said cap members together against relative rotary movement. 5

3. In a cap of the character described, a main cap member provided with a threaded socket for threaded engagement with the neck of a bottle, a false cap member housing the main cap member and normally free to rotate relative to the main cap member, a spring device interposed between the crown ends of said cap members for normally spacing said crown ends relative to one another, and inter-engaging means on said crown ends of said cap members adapted to be engaged in opposition to said spring means for transmitting movement of the false cap member to the main cap member. 10 15
